[57] CLAIM

The ornamental design for a citrus fruit juice extractor, as shown.

DESCRIPTION

FIG. 1 is a front elevational view of a citrus fruit juice extractor showing my new design;

FIG. 2 is a sectional, elevational view thereof, taken on the line 2—2 of FIG. 1;

FIG. 3 is an elevational view of one of the two identical sides thereof;

FIG. 4 is a top plan view thereof; and

FIG. 5 is a fragmentary, rear elevational view thereof.
